UNITED STATES PATENT OFFICE

DEAN S. BARNARD, OF HINSDALE, ILLINOIS, ASSIGNOR TO THE ROME COMPANY, INC., A CORPORATION OF NEW YORK

COILED SPRING CUSHION

Application filed June 15, 1931. Serial No. 544,489.

The present invention has for its object a simple and novel means for tying together corresponding intermediate coils of bed spring structures of the vertical, coiled spring type, whereby the structure is stiffened against lateral swaying without impairment of its cushioning qualities.

The various features of novelty whereby my invention is characterized will herein-
10 after be pointed out with particularity in the claims; but, for a full understanding of my invention and of its objects and advantages, reference may be had to the following detailed description taken in connection with
15 the accompanying drawings, wherein:

Figure 1 is a top plan view, showing more or less diagrammatically a bed spring of a well known type to which my invention is applied, only fragments of the "cushion" portion being shown; Fig. 2 is a horizontal section, on a much larger scale than Fig. 1, through a corner of the spring, looking downward, the section being taken approximately on line 2—2 of Fig. 3; Fig. 3 is an edge view
20 of a corner of the spring, on the same scale as Fig. 2; Fig. 4 is a section taken approximately on line 4—4 of Fig. 3; and Figs. 5 and 6 are sections, on a still larger scale, taken, respectively, on lines 5—5 and 6—6 of Fig. 2.

Referring to the drawings, 1 represents a heavy bottom frame from which rise vertical coiled springs 2 arranged in rows that extend transversely of the supporting frame and also longitudinally. The upper coils of the
30 springs may be connected together by small, diagonal helical springs 4 or in any suitable way. In fact, all of the structure thus far described is old and well known in various forms to which my invention is applicable.

In accordance with my invention, corresponding intermediate coils of all of the springs in each row are connected together by ties so that each spring will be aided by all of the other springs in resisting lateral or
40 swaying movements. However, in accordance with my invention, these ties are of such a character that each spring may be compressed and expanded without meeting any appreciable resistance from the other springs or the ties. This result is brought about by

hinging the actual ties, which are the parts extending across the spaces between adjacent springs, to the springs.

Since there are a great many vertical springs in a bed spring, many hinges are required, and I have, therefore, produced a simple and novel arrangement for effectively hinging the ties to the springs in such a manner that relative movements of the hinge joints will not make audible sounds.

The ties themselves may conveniently be made of light wire and be attached to the springs by simple anchoring plates. In the arrangement shown, the anchoring members are in the form of sheet metal plates 5 cut away at the center so as to permit them to surround the springs. In removing the metal from the centers of the plates, I leave diametrically opposed tongues 6. In applying an anchoring plate to a spring, it is run along the wire of the spring until brought into the plane of the intermediate coil, indicated at A in the drawings, to which it is to be secured, the tongues overlying such coil. The tongues are then bent around the wire of the spring
70 and serve securely to hold the plate. At four points along the periphery or edge of the plate, spaced 90° apart, are tongues bent downwardly into tubes forming hinge ears 7; each plate being fastened to its spring in such a manner that a hinge ear or a set of hinging ears lies on each side thereof nearest the two adjacent springs in either transverse or longitudinal row. The actual ties may be endless frames 8 in the form of long, narrow rectangles composed of comparatively light wire; the width of each frame being only slightly greater than the length of one of the hinge ears or sets of ears; whereby each short frame element of a tie may serve also as a hinge pintle, being surrounded by one of the hinge ears or sets of ears.

It will be seen that each spring, except those of the outermost row, is at the center of a square at whose corners are four other springs, and whose sides form angles of 45° with the longitudinal and transverse axes of the spring assembly so that the tie elements form diagonals of this square and each may
90 100

swing at either end about a horizontal axis at right angles to the length thereof.

There is preferably employed another frame 9, similar to the frame 3, but lying in the plane of the anchoring plates. One ear 10 or set of ears on the outer side of each of the anchoring plates on the outermost springs may be bent around the wire of the frame 9 so as to hold this frame to the springs.

10 In order to reduce the number of wires close to the edge of the spring structure as a whole, the tie elements 11 between the springs of the outermost rows may be similar to those that have been described, except that one long side or frame member is left off, giving these ties the form of a single wire having its ends bent laterally in the same direction to form hinge pintles.

20 The vertical springs 2 are supported from the bottom frame 1 in any suitable way as, for example, by members or elements 13 extending across the frame 1 from side to side and members or elements 14 extending across the frame from end to end; there being an element or member 13 and an element or member 14 crossing each other underneath each spring.

It is believed that the operation, as well as the construction of my improvements, has 30 been sufficiently explained. It will be seen from the left-hand side of Fig. 5, however, that the tie wires may swing up and down relatively to their anchoring plates, so that the anchoring plate on any spring that must 35 sustain a heavy load may remain horizontal as the spring is compressed and the plate moves down.

While I have illustrated and described with particularity only a single preferred form of 40 my invention, I do not desire to be limited to the exact structural details thus illustrated and described; but intend to cover all forms and arrangements which come within the definitions of my invention constituting the appended claims.

I claim:

1. The combination with a spring cushion comprising a bottom spring-supporting frame and a superstructure including vertical coiled springs mounted on the frame and arranged in transverse and longitudinal rows, of ties extending from an intermediate coil of each spring to the corresponding coils of the adjacent springs in each transverse 55 and longitudinal row, a ring-like metal plate lying outside of and surrounding and secured to each of said intermediate coils, each plate having at the periphery hinge ears each registering with the corresponding tie and extending transversely thereto, and the end portions of the ties extending laterally into said hinge ears.

60 2. The combination with a spring cushion containing vertical coiled springs arranged 65 in transverse and longitudinal rows whereby

each inner spring is at the center of a square at the four corners of which are four other springs, of ring-like metal plates lying outside of and surrounding and fixed to corresponding intermediate coils of the springs, a tie in the form of a long, narrow rectangular frame extending from each spring in the center of a square to each spring of the corner of that square, and hinge ears on each plate surrounding the adjacent narrow frame members of the ties radiating therefrom.

3. The combination with a spring cushion comprising a bottom spring-supporting frame, vertical coiled springs mounted thereon and arranged in transverse and longitudinal rows, and a top frame extending along and connected with the upper ends of the outermost springs: of a tie structure between the springs comprising a ring-like metal plate lying outside of and surrounding and fastened to each spring, ties extending from each plate to the plates associated with the four adjacent springs in the corresponding longitudinal and transverse rows, and hinge connections between the plates and the ties, the hinge axes being horizontal and those for the longitudinal ties being transverse to the cushion while those for the transverse ties are longitudinal of the cushion.

4. The combination with a spring cushion comprising a bottom spring-supporting frame and a superstructure including vertical coiled springs mounted on the bottom frame and arranged in transverse and longitudinal rows, of ring-like metal plates surrounding and fixed to corresponding intermediate coils of the springs, each plate having thereon four hinge ears on the sides facing four surrounding springs, and ties connecting the hinge ears on each spring with the near hinge ears on the four surrounding springs.

5. The combination with a spring cushion comprising a bottom spring-supporting frame and a superstructure including vertical coiled springs mounted on the bottom frame and arranged in transverse and longitudinal rows, of ring-like metal plates surrounding and fixed to corresponding intermediate coils of the springs, each plate having thereon four hinge ears on the sides facing four surrounding springs, ties connecting the hinge ears on each spring with the near hinge ears on the four surrounding springs, a light frame surrounding the superstructure in the plane of said coils, and the adjacent hinge ears on the plates of the outer springs surrounding the members of the frame and securing the frame to the springs.

In testimony whereof, I sign this specification.

DEAN S. BARNARD.
